UNITED STATES PATENT OFFICE.

WILLIAM R. JENKINS, OF BELLEFONTE, PENNSYLVANIA.

OIL-BURNER.

SPECIFICATION forming part of Letters Patent No. 532,379, dated January 8, 1895.

Application filed November 4, 1893. Serial No. 490,039. (No model.)

To all whom it may concern:

Be it known that I, WILLIAM R. JENKINS, of Bellefonte, county of Center, State of Pennsylvania, have invented certain new and useful Improvements in Oil-Burners, of which the following is a specification, reference being had to the accompanying drawings.

The object of my invention is to produce improvements in retort vaporizing hydrocarbon burners by which the efficiency of the burner is increased; the combustion of the fuel is more completely effected; and the efficiency of the burner under a low pressure of oil is improved. At the same time, by my invention, the adaptability of the burner for use in exposed localities is enlarged.

In the accompanying drawings: Figure 1 is a side elevation of my burner. Fig. 2 is a view taken at right angles thereto. Fig. 3 is a section on the line *a*—*b* of Fig. 1. Fig. 4 is a section on the line *c*—*d* of Fig. 2. Fig. 5 is a top plan view of the base of the burner.

Referring to the figures on the drawings, 1 indicates a flange which, with a diaphragm 2, preferably constitutes the dish-shaped base of my burner within which, as will herein-after appear, takes place the initial combustion or priming of the machine.

3 indicates a generator which preferably consists of a hollow casting provided with hollow legs 4 communicating with the interior thereof. This interior is supported upon the base by suitable means, preferably by a tube 5, screwing into an opening 6 in the base 35 and into one of the hollow legs 4. The opening 6 constitutes the oil supply opening and it is designed to communicate with a source of oil supply, not illustrated. The remaining leg 4 carries a tube 7 which extends upwardly 40 into the generator above its bottom wall, as is clearly illustrated in Fig. 4 of the drawings.

Near its lower end the tube 7 is provided with a vent 8 and is bent so as to bring the vent directly under the middle part of the axis of the generator. This middle part, as illustrated, consists of a removable plug 9 tightly fitting within and completely closing a central aperture 10 that extends entirely through the generator. A cylindrical wall 50 11 defines the aperture 10 and the interior space of the generator. The lower end of the plug 9 and the exterior of the bottom

wall of the retort are finished flush with each other and are, collectively, somewhat inversely conoidal in shape, the axis 12 of the 55 plug forming the apex. The office of the aperture 10 being exclusively for affording admission of a cleaning instrument, and the presence of the plug being essential to the operation of the burner, the central part of 60 the generator might be made solid, the aperture 10 being altogether omitted. Since, however, they afford convenient means of gaining access to the burner for cleaning purposes, I prefer to employ a central aperture 65 in connection with the plug.

13 indicates a combustion chamber, preferably cylindrical in shape and preferably fixedly supported by a pair of air supply branches or ducts 14, a little above the vent 70 8. The number of air branches is immaterial and they are employed to support the combustion chamber because, their object being to supply thereto fresh air drawn preferably from beneath the plane of initial combustion, 75 they may be conveniently cast with the case and the combustion chamber in one piece. By the arrangement illustrated, an air space 15 communicating with the lower part of the combustion chamber is provided around the 80 lower end of the pipe 7 and adjacent to the vent 8.

16 indicates an annular disk or flange preferably adjustably carried between the combustion chamber and the generator and in 85 close proximity to both. Its office is to protect the flame while passing out under the generator from upward currents of air.

In operation, oil supplied through the opening 6 passes through the tube 5 into the 90 interior of the generator and, rising above the end of the tube 7, is allowed to pass through the vent 8 into the dish-shaped base until enough has accumulated there to support an initial combustion, when the flow of 95 oil is stopped. The oil in the base is then ignited and the products of the combustion, passing up against the bottom of the generator, vaporize the oil contained therein, whereupon the vapor, passing out of the vent 8, is 100 ignited and, supported by the air within the combustion chamber 13, issues from the upper end thereof in a clear flame. This flame, striking against the deflecting conoidal bot-

tom of the generator, is distributed over the surface and serves to keep the generator in continuous and perfect operation. After the process of vaporization has been commenced 5 within the generator, the oil necessary to the initial combustion is quickly consumed, being no longer required.

One advantage of providing the generator with a deflecting bottom in a burner of this 10 class and locating the combustion chamber below it, is that all the heat from the combustion chamber exerts its effect upon the generator so that it is possible to keep the burner going with the lowest oil supply pressure. Without this arrangement, when the 15 pressure is reduced below a certain point, the generator becomes too cool, the vapor ceases to pass out from the jet, and the flame becomes extinguished.

20 Another advantage of this form of burner, relating especially to the locating of a combustion chamber in close proximity to the jet beneath the generator and in communication with air supply branches communicating 25 with the pure air below the plane of initial combustion, is that the air is supplied directly to the place where it is most needed to promote perfect combustion while the burner is in full operation. Moreover, the combustion 30 chamber tends to protect the vent 8 from the fumes of the initial combustion, which would otherwise tend to exclude or vitiate the fresh air supplied through the branches or ducts 14. This smothering of vapor which first is

sues from the vent 8 is not only wasteful and 35 therefore objectionable, but tends to produce an accumulation of carbon upon the parts, which tends to interfere with the perfect operation of the machine.

What I claim is—

1. In a hydro-carbon burner, the combination with a burner and superimposed generator communicating therewith, of an aperture in the generator extending entirely through the generator, a plug fitting within 45 the aperture, the lower end of the plug and the exterior of the bottom of the generator being finished flush with each other and forming collectively an inversely conoidal bottom, substantially as set forth. 50

2. In a hydro-carbon burner, the combination with a base and generator connected therewith, of a tube communicating with the generator and extending underneath the same, a vent within the tube, a combustion 55 chamber located between the generator and the vent, air supply branches communicating with the combustion chamber, the inner walls of said air supply branches defining an air space in the combustion chamber around 60 the end of the tube containing the vent, substantially as and for the purpose specified.

In testimony of all which I have hereunto subscribed my name.

WILLIAM R. JENKINS.
